UNITED STATES PATENT OFFICE.

ANDREW J. GILBERT, OF NEW YORK, N. Y., ASSIGNOR TO THE UNION STOVE
AND MANUFACTURING COMPANY, OF PITTSTON, PENNSYLVANIA.

DESIGN FOR A RANGE.

Specification forming part of Design No. 6,318, dated December 17, 1872.

CASE A.

To all whom it may concern:

Be it known that I, ANDREW J. GILBERT, of the city, county, and State of New York, have invented a new and original Design for a Range, called "The Excello Range," of which the following is a specification:

The accompanying photograph fully illustrates my invention.

This invention relates to several new features in the design for a range. It consists in the new form of octagonal panel ornaments and moldings around the lower part of the range, said panels containing cross-shaped central decorations. The invention also consists in a new form of center ornament for the side doors of the range, within each of which the letters "X. L. O." are applied. Furthermore, the invention consists in the new arrangement of moldings for such side doors; also, in the new arrangement of panels on the ends of the range, and in the new form

of moldings of the range generally. Finally, the invention consists in forming a projecting step-molding between the upper and lower parts of the range, whereby the lower part is enlarged, as seen.

I claim as my invention—

1. The design for the lower panel ornaments of a range, as shown.
2. The design of the center ornaments of the side doors, as shown.
3. The design of the moldings of the side doors, as shown.
4. The design for the end panels of the range, as shown.
5. The design of the projecting step-molding on the range, as shown.

ANDREW J. GILBERT.
